COMBINATION WINDOW

Oscar J. Niquette, Nashua, N. H.

Application May 26, 1950, Serial No. 164,531

2 Claims. (Cl. 268—130)

1

This invention relates to new and useful improvements in window construction, and more particularly pertains to means for operating the window closing members.

The primary object of this invention is to provide a permanent window installation which will be fully satisfactory in performance irrespective of the season of the year, and which will obviate the hazardous and inconvenient annual procedure of installing and removing storm sash.

Another important object of this invention is to provide a window construction capable of realizing the foregoing object and that will be self-cleaning in operation.

Another object of the present invention is that the same may be readily applicable to existing building constructions.

Another object of the present invention is to provide a window construction in which the window sash may be moved out of the window opening and out of sight and into a receiving chamber within the wall proper, and to provide mechanical means making such movement easy and not requiring difficulties customarily associated with opening and closing windows.

Still another important object of this invention is to provide a window construction wherein the windows may be positioned so as to not obstruct the window opening at all.

An important feature of the present invention resides in the means provided for moving the windows, and the positioning of the flexible components thereof so as to permit independent selective positioning of the windows.

Another important feature of the present invention resides in the wiper block which serves the dual functions of preventing the entry of foreign matter into the sash-receiving chamber, and wiping and cleaning the windows during sliding movement of the same.

A final important feature to be specifically enumerated herein resides in the provision for a drain in the sash receiving chamber, and the provision of a fixed pane in the window opening which may be used when it is desired to have a window frame having an opening larger than the size of the sash-receiving chamber.

These, together with various ancillary features and objects of the invention which will later become apparent as the following description proceeds, are attained by the present invention, a preferred embodiment of which has been illustrated by way of example only in the accompanying drawings, wherein:

Figure 1 is a side elevational view of the pres-

2

ent invention showing the same installed in a wall, and with portions of the wall being broken away and shown in section, this view being taken substantially upon the plane of the broken section line 1—1 of Figure 2;

Figure 2 is a transverse vertical sectional view of the present invention, this view being taken upon the plane of the section line 2—2 of Figure 1; and

10 Figure 3 is a perspective view of the windows and the means for actuating sliding movement of the same.

Reference is now made more specifically to the accompanying drawings, wherein like numerals 15 designate similar parts throughout the various views, and in which the wall of a building is designated generally at 10. The wall 10 conventionally includes outer and inner wall sections 12 and 14, respectively, joined by studs 16.

20 Mounted within the wall 10 is a window frame designated generally at 18 which includes side members 20 joined at their upper and lower ends respectively by a lintel 22 and a sill 24. The window opening 26 defined by the window frame 18 has fitted therein a screen 28 carried by the frame 18, and the side members 20 of the frame 18 are provided with a pair of window sash guiding channels 30 and 32 for guiding sliding movement of window closing members 34 and 36, respectively. It will be understood that the members 34 and 36 may be provided with frames of conventional design or may be merely panes of glass or the like.

25 The sill 24 is provided with a pair of slots 38 and 40 in alignment with the sliding movement of the members 34 and 36, respectively, whereby the members 34 and 36 can slide downwardly through the sill 24 into a chamber 42 below the sill 24 between the studs 16 and the inner and outer wall sections 14 and 12. Wiper blocks 44

30 are secured to the sill 24 immediately adjacent the slots 38 and 40, such blocks 44 being of suitable wiping material, such as rubber or the like, 35 and in sliding engagement with the members 34 and 36 for wiping and cleaning the latter upon sliding movement of the same, and also for the purpose of preventing water or the like gaining 40 access to the chamber 42 through the slots 38 and 40.

35 A receptacle 46 having a sloping bottom 48 closes the bottom of the chamber 42 for collecting any moisture that inadvertently gains access to the chamber 42, and which receptacle 46 is 45 provided with a downwardly sloping drain tube

50 55

50 that extends outwardly through the outer wall section 12.

Means is provided whereby the window closing members 34 and 36 may be selectively moved into and out of the window opening 26 either manually or by the use of electric motors. Such means include a pair of rotatably mounted shafts 52 and 54 adjacent the upper end of the chamber 42. The shafts 52 and 54 are preferably in longitudinal alignment, and the shaft 54 is for the purpose of raising and lowering the member 34, while the shaft 52 is for the purpose of raising and lowering the member 36. The shaft 54 is provided with a pair of drums 56 and 58 upon which are wound in opposite directions the flexible elements 60 and 62, respectively, such elements being preferably thin bands of steel. As clearly shown in Figure 3, the free end of the element 60 is provided with a hook 64 which engages the upper end of the member 34, while the free end of the element 62 is provided with a similar hook 66 that engages the lower edge of the member 34, the arrangement being such that upon rotation of the shaft 54 one of the elements 60 and 62 is played out while the other is taken up so as to raise or lower the member 34, depending upon the direction of rotation of the shaft 54, as will be readily understood. Alternate means is provided for rotating the shaft 54 which includes a shaft 68 that is journaled through the inner wall section 14 having its inner end connected to the shaft 54 by means of bevel gears 70 and its outer end provided with a crank 72. As thus far described, it will be seen that the member 34 may be manually raised or lowered by turning the crank 72.

Mounted upon a bracket 74 within the chamber 42 is an electric motor 76 of the reversible type which is provided with a control switch mechanism 78 extending through the inner wall section 14 whereby the motor 76 may be selectively controlled to operate either in a clockwise or anti-clockwise direction. The driving shaft 80 of the electric motor 76 is operatively connected to the shaft 54 by means of a pulley 82 and a pulley 84 having a flexible drive belt 86 entrained thereover. It will thus be seen that the window closing member 34 may be either raised or lowered by the use of the crank 72 or by means of the electric motor 76 and the control 78 therefor.

In order to raise or lower the window closing member 36, a further electric motor 88 is mounted within the chamber 42 upon a bracket 90, and this motor is likewise provided with a control 92 similar to the control 78 for the other electric motor, and it will be understood that the motor 88 is similar to the motor 76. The electric motor 88 is drivingly connected to the shaft 52 by means of a flexible belt 94 and pulleys 96 and 98, whereby the shaft 52 may be rotated either clockwise or anti-clockwise by means of the motor 88 and the control 92. In addition, manually operated means 100 similar to those provided for the shaft 54 are provided for rotating the shaft 52.

The shaft 52 is provided with a pair of drums 102 and 104 upon which drums are oppositely wound flexible elements 106 and 108, the arrangement being such that upon rotation of the shaft 52, one of the elements 106 or 108 is played out while the other is taken up. In order that the elements 106 and 108 will clear the member 34 when the latter is disposed within the chamber 42, the elements 106 and 108 extend downward-

ly from the drums 102 and 104 and are entrained respectively under idler pulley assemblies 110 and 112, respectively, that are suitably mounted upon the bottom wall 48 of the receptacle 46 immediately below the window-closing member 34. The flexible elements 106 and 108 then extend upwardly from the pulley assemblies 110 and 112 with the flexible element 108 extending upwardly through the slot 40 to be secured at its free end to the upper edge of the member 36 by means of a hook 114. The flexible element 106 extends upwardly from the idler pulley assembly 110 to be entrained over a further idler pulley 116 carried by the sill 24 and extends downwardly therefrom to have its free end secured to the lower edge of the member 36 by a hook 118. It will be readily seen that when the shaft 52 is rotated to take up the flexible element 108 upon the drum 104 that the tension thus produced in the element 108 will draw downwardly upon the member 36, while opposite rotation of the shaft 52 will tension the element 106 to draw the member 36 upwardly.

Since it is occasionally desired to have large windows which would impose space limitations on the chamber 42 that would not ordinarily permit the window-closing members to be fully retracted into the chamber, means are provided at the upper edge of the window opening 26 which will permit the passage of light through such a large opening and yet which would permit the window-closing members to be fully retracted into the chamber 42. Such means comprise parallel panes 120 disposed at the upper end of the window opening 26 which are suitably spaced and retained in fixed position by frame members 122 and 124. As shown in Figure 2, the frame member 124 is in alignment with the path of travel of the window closing members 34 and 36 and is provided with grooves 126 in its lower edge for receiving the upper edges of the window-closing members 34 and 36.

It will thus be seen that there has been provided a construction of extreme flexibility and utility, which will permit either of the window-closing members 34 or 36 to be independently and adjustably positioned within the window opening 26 to any desired extent, and that such arrangement has the particular advantage of affording the insulative and moisture formation resistive characteristics of storm sash in combination with the usual window sash and frame construction.

Since, from the foregoing, the construction and advantages of this combination window are readily apparent, further description is believed to be unnecessary.

However, since numerous modifications and equivalents will readily occur to those skilled in the art after a consideration of the foregoing specification and accompanying drawings, it is not intended to limit the invention to the exact embodiment shown and described, but all suitable modifications and equivalents may be resorted to which fall within the scope of the appended claims.

Having described the invention, what is claimed as new is:

1. In window construction, inner and outer vertically slidably windows, means for operating the outer window comprising a rotatable horizontal shaft disposed inwardly of the inner window, flexible means operatively connected to the shafts and including first and second portions extending from the shaft, said flexible means

being so constructed and arranged with respect to the shaft that rotation of the latter in one direction retracts one of the portions while extending the other, a pair of guide pulleys disposed below the lowest point to which the inner window will extend, said first portion being entrained under one of the pair of pulleys and extending upwardly therefrom and having its free end secured to the outer window, a further guide pulley disposed outward of said other window above 10 said pair of pulleys, said second portion being entrained under the other of the pair of pulleys and extending upwardly therefrom, thence being entrained over the further pulley and extending downwardly therefrom with its free end secured to the outer window, whereby the flexible means does not interfere with vertical adjustment of the inner window and the outer window may be raised or lowered by rotating the shaft in the appropriate direction.

2. In window construction, inner and outer vertically slideable windows, means for operating the windows comprising first and second horizontal rotatable shafts disposed inwardly of the windows, flexible means operatively connected to each of the shafts including first and second portions extending from the shaft, said flexible means being so constructed and arranged with respect to each of the shafts that rotation of one of the shafts retracts one of the portions associated therewith while extending the other portion associated therewith, the first portion connected to the first shaft extending upwardly therefrom and having its free end connected to the inner window, the second portion connected to the first shaft extending downwardly therefrom and having its free end connected to the inner window, a pair of idler pulleys disposed below the lowest point to which the inner window will extend, the first portion connected to the 40 second shaft being entrained below one of the

5 idler pulleys and extending upwardly therefrom and having its free end connected to the outer window, a further guide pulley above said idler pulleys, the second portion connected to the second shaft being entrained under the other of the pair of idler pulleys, thence extended upwardly and entrained over the further pulley, thence extending downwardly and having its free end connected to the outer window.

OSCAR J. NIQUETTE.
